UNITED STATES PATENT OFFICE

HENRY J. SAUER, OF FAIRFIELD, CONNECTICUT, ASSIGNOR TO THE KILBORN-SAUER COMPANY, OF FAIRFIELD, CONNECTICUT, A CORPORATION OF CONNECTICUT

DESIGN FOR A REFLECTOR

Application filed December 12, 1929. Serial No. 33,764. Term of patent 3½ years.

To all whom it may concern:

Be it known that I, HENRY J. SAUER, a citizen of the United States, residing at Fairfield, in the county of Fairfield and State of Connecticut, have invented a new, original, and ornamental Design for a Reflector, of which the following is a specification, reference being had to the accompanying drawing, forming part thereof.

In the drawings—

Fig. 1 is a rear elevation of my reflector;
Fig. 2 is a side or edge view thereof.

I claim:

The ornamental design for a reflector, as shown.

HENRY J. SAUER.
